MACHINE FOR SHAPING UPPERS OVER
LASTSAxel E. Lindblad, Orange, N. J., assignor to
United Shoe Machinery Corporation, Paterson,
N. J., a corporation of New Jersey

Application November 4, 1931. Serial No. 572,982

32 Claims. (Cl. 12—2)

This invention relates to machines for shaping uppers over lasts, and is herein illustrated as applied to a lasting machine having means for pulling an upper over a last successively in different locations along the edge of the shoe bottom and means for laying the marginal portion of the upper inwardly over the bottom of the last in time relation to each upper-pulling operation, the machine herein shown having also means for fastening the upper by driving staples and curving their legs progressively as they are driven to anchor them in the shoe, as disclosed in Letters Patent No. 1,815,295, granted on July 21, 1931 upon an application of George Goddu.

It is to be understood, however, that the invention in its more general aspects is not limited to machines of the particular type illustrated.

An object of the invention is to provide, in a machine for shaping uppers over lasts, improved means for laying the marginal portion of an upper inwardly over a sole or insole (hereinafter frequently referred to generically as the sole). Machines of the type disclosed in the above-mentioned Letters Patent include in their organization overlaying means that operates on the upper by movement in a direction inclined toward the bottom face of the last, so as to lay the upper over the sole without the necessity for great care on the part of the operator in positioning the shoe with the edge of the sole in an exact relation to the overlaying means. The present invention, in one important aspect, provides overlaying means which, while mounted for movement into position to operate on the shoe in such inclined relation to the bottom face of the last, is arranged to be deflected by the shoe so that it follows a path substantially parallel to the bottom face of the last in laying the upper over the sole. Preferably, as illustrated, an overlaying wiper movable as above described is arranged to engage the upper first with the forward end of its upper-engaging portion substantially at the edge of the shoe bottom and then, when deflected by the shoe, acts yieldingly to wipe the upper over the sole, the wiper having a wiping face which engages the upper from the edge of the sole inwardly in substantially parallel relation to the bottom of the last at the end of the overlaying operation. The upper is, therefore, wiped tightly inward from the edge of the sole and is thereafter pressed substantially flat upon the outer face of the sole over a considerable area, the construction shown further including means for pressing the wiper positively upon the upper at the end of the wiping

movement. Such overlaying means is herein shown as combined with mechanism of the character disclosed in the above-mentioned Letters Patent for fastening the upper with a staple at the end of each overlaying operation, and is further illustrated as applicable to the laying of the marginal portion of the upper over the sole in lasting a shoe with cement instead of with driven fastenings.

The novel features of the invention, including various novel details of construction and combinations of parts, will now be more particularly described by reference to the accompanying drawing and pointed out in the claims.

In the drawing, Fig. 1 shows mainly in side elevation a portion of a machine in which the invention is embodied, illustrating the positions of the parts at the end of the overlaying and staple-driving operations;

Fig. 2 is a view similar to Fig. 1 of a portion of the structure there shown, but illustrating the positions of the parts substantially at the beginning of the overlaying operation;

Fig. 3 is a view similar to a portion of Fig. 1, but illustrating the laying of the upper over an insole in lasting with cement instead of with staples;

Fig. 4 is an inverted plan view on an enlarged scale of a portion of the overlaying means; and

Fig. 5 is a section on the line V—V of Fig. 4.

Since the invention is herein illustrated as embodied in a machine of the same type as disclosed in the above-mentioned Letters Patent, only such portions of the machine as it is necessary particularly to refer to for an understanding of the invention are herein shown and will be described in detail.

It will be understood that the shoe and last are supported bottom upward in the hands of the operator and presented successively in different positions in the progressive lasting, for example, of the opposite sides of the shoe along its fore-part and shank portions. To assist in determining the proper relation of the shoe to the lasting instrumentalities the machine is provided with a side gage 10 arranged to engage the side of the shoe at or near the edge of the insole and with a sole rest 12 for engaging the bottom face of the insole at a considerable distance from its edge. The upper is pulled over the last and inwardly over the insole when the shoe is in each lasting position by a gripper comprising a pair of jaws 14. For laying the marginal portion of the upper inwardly over the insole and fastening it with staples there is provided a slide or

carrier 16 which is moved by a cam (not shown) along a straight guideway 18 in a forwardly and downwardly inclined direction at an angle to the bottom face of the last and shoe. This slide 5 carries a staple guide or nozzle 20, a staple driver 22 and a deflector 24 which engages the legs of the staple and curves them prior to and during their entrance into the shoe so that they are anchored in the insole without necessarily emerging from its inner face, as illustrated in Fig. 1. The operative movement of the driver is in a rearward direction, away from the operator's working position, and the deflector curves the legs of the staple forwardly away from the 10 rear edge of the insole. It will be understood that prior to the driving of the staple the marginal portion of the upper, pulled inwardly over the insole by the gripper, is laid over and upon the outer face of the insole by the forward movement of the slide 16. Substantially at the end 15 of the forward movement of the slide along the guideway 18 the staple nozzle and deflector receive a short downward movement more directly toward the shoe bottom which is effected by 20 swinging the slide 16 about the axis of a rock shaft 26 (Fig. 1). For this purpose a member 28 on which the guideway 18 is formed is mounted on a holder 30 which is fast on the rock shaft 26, and fast also on the rock shaft is a 25 lever 32 operated by a cam (not shown) to swing the slide 16 as described. In this manner insurance is afforded that the upper will be pressed firmly upon the insole and that the staple nozzle and deflector will be close to the shoe bottom 30 when the staple is driven.

Means substantially as disclosed in the above-mentioned Letters Patent is provided for operating the staple driver 22. The driver is fastened to a driver slide 34 which is movable in a 35 guideway formed in a bracket 36 secured to a forward extension of the slide 16. The driver slide 34 is operated by a lever 38 which is pivoted on a stud 40 on a forward extension of the slide 16 and carries a lug 42 extending into a recess in the driver slide. The lever 38 is operated by a bell-crank lever 44 which is pivoted on a rod 46 on the slide 16 and is operated by a torsion spring (not shown). A forwardly extending 40 arm of the bell-crank lever 44 carries a roll 48 which operates in a cam slot 50 in the lever 38, the cam slot being so formed that the staple-driving movement is imparted to the lever 38 by upward movement of this arm. For swinging the bell-crank lever 44 against the resistance of its 45 operating spring to retract the driver 22 and tension the spring, there is pivoted at 52 on the head of the machine a lever 54 on which is pivotally mounted at 56 a latch 58 arranged to engage the lower end of a plate 60 fast on a downwardly extending arm of the bell-crank lever 44. A spring 62 connected to the latch 58 and to a pin 64 on the lever 54 holds the latch in operative relation to the plate 60 when the slide 16 and the 50 parts carried thereby are in their initial positions.

When the slide is moved forwardly toward the shoe the latch 58 acts to swing the bell-crank lever 44 against the resistance of its spring in response to such forward movement, thereby operating the lever 38 to retract the staple driver 22 as the latter is being carried bodily forward by the slide. For operating the latch 58 to release the lever 44 and thus to cause the operation of the driver, the slide 16 carries a screw 66 the head of which is arranged to engage a shoulder on the 55 latch as illustrated in Fig. 1. The forward move-

ment of the slide 16, however, does not carry the screw far enough to release the lever 44, such release being effected in response to a swinging movement of the latch-carrying lever 54 effected by a cam (not shown) after the slide 16 has completed its forward movement. It will be understood that by reason of such movement of the lever 54 the screw 66 causes the latch 58 to swing far enough to disconnect it from the plate 60. In the return of the parts to starting positions the latch 52 is held by a shoulder 68 on the lever 54 in position to connect again with the plate 60 when the slide 16 arrives at the end of its retractive movement.

The machine is also provided with means for forming a staple in response to the forward movement of the slide 16 and for transferring the staple from forming position into alignment with the driver 22, together with means for feeding wire intermittently to the staple-forming means and mechanism for interrupting the feed of the wire when desired so that no staple will be formed in the operation of the machine, in case, for example, it is desired to use the machine to last a shoe or a portion thereof with cement instead of 100 with staples. These parts are not shown in detail, since it will be understood that in these and other respects the construction of the illustrated machine as thus far described is substantially as disclosed in the above-mentioned Letters Patent. 105

For purposes of this invention there is provided an overlaying member 70 which as herein illustrated is arranged to act as a wiper to wipe the marginal portion of the upper inwardly from the edge of the insole in each cycle of operations of the machine. This member is pivoted at 73 on a supporting plate 72 which is fastened by screws 76 and 78 to the slide 16 upon the lower face of a bracket 80 which supports the nozzle 20 and the deflector 24. The member 70 is provided with spaced arms 82 and 84 located at opposite sides of an extension 86 of the plate 72, the arm 82 being extended farther than the arm 84, as illustrated in Fig. 4, and provided with a stud 88 engaged by one end of a spring 90 which is mounted on a stud 92 on the plate 72, the other end of the spring 90 being held by a stud 94 on the plate. It will thus be seen that the spring 90 tends to swing the member 70 downwardly, such downward movement of the member being limited by its engagement with a shoulder 96 on the extension 86, as shown in Fig. 5. The member 70 extends a considerable distance lengthwise of the edge of the shoe bottom at each side of the deflector 24 and is provided with a recess 98 into which the lower portion of the deflector extends, the deflector being arranged to limit upward swinging movement of the member by contact therewith. The member 70 is provided at its forward end with a lower face 100 for wiping engagement with the upper.

In operation, as the slide 16 carrying the staple nozzle and deflector is moved in its downwardly and forwardly inclined direction, imparting to the supporting plate 72 and the member 70 movement in a straight path inclined toward the bottom face of the shoe, the forward end of the upper-engaging portion of the member 70, i. e., the end or edge thereof that is farthest from the edge of the shoe bottom when the member completes its wiping movement, first engages the upper in a location substantially at the extreme edge of the shoe bottom, as illustrated in Fig. 2, the upper being held at this time under ten-

sion by the gripper 14 which, as disclosed in the previously-mentioned Letters Patent, is displaced somewhat lengthwise of the edge of the shoe bottom from the overlaying and fastening devices. As the movement of the slide 16 continues the member 70 is deflected by the shoe so as to follow a path substantially parallel to the bottom face of the last and thus serves as a wiper to wipe the upper inwardly from the edge of the shoe bottom while yielding against the resistance of the spring 90 as the staple nozzle and deflector approach more closely to the shoe bottom. At the end of the movement of the slide 16 the deflector 24 preferably engages the member 70 so as to act positively thereon to increase the pressure of the member on the upper as the slide 16 is tipped about the axis of the rock shaft 26 in the manner hereinbefore described. By reference to Fig. 1 it will be seen that at the end of the overlaying operation the lower wiping face of the member 70 is in engagement with the upper from the edge of the shoe bottom inwardly in substantially parallel relation to the bottom of the last and thus serves as effective means to press the upper smoothly and firmly downward upon the shoe bottom after having wiped it tightly inward from the edge of the insole. It will be understood that substantially at the end of the forward movement of the slide 16 the gripper 14 releases the upper.

The machine herein shown is also provided with additional means to assist in pressing the upper smoothly and firmly upon the insole in a location farther inwardly from the edge of the shoe bottom than the member 70. This means comprises a stirrup-shaped member 102 which embraces a portion of the staple nozzle 20 and is fastened thereto, this member having a lower face arranged to press on the upper in substantially the same plane as the lower face of the member 70 at the end of the overlaying operation. It will be evident that the member 102 is especially useful in operating on shoes the uppers of which extend inwardly over the insole considerably beyond the locations of the upper-fastening staples. The members 70 and 102 combined thus provide means for pressing the lasting margin of the upper upon the insole throughout approximately the whole width of the margin, so that the upper will be pressed flat and held firmly upon the insole at the time when each staple is driven.

It is contemplated that in addition to the above described and other advantages in the use of the overlaying means herein shown in preparing the upper to receive fastenings driven into the shoe bottom, such means will also be especially useful in lasting shoes or portions thereof with cement instead of with driven fastenings, as illustrated in Fig. 3, since the marginal portion of the upper will be wiped tightly inward from the edge of the shoe bottom and pressed firmly and evenly upon the insole in position to adhere to the insole.

Having described the invention, what I claim as new and desire to secure by Letters Patent of the United States is:—

1. In a machine for shaping uppers over lasts, a member for laying the marginal portion of an upper inwardly over a sole on a last, said member being movable into position to act on the upper in a straight path inclined toward the bottom face of the last and arranged to be thereafter deflected by the shoe in a path substantially parallel to said face in laying the upper over the sole.

2. In a machine for shaping uppers over lasts,

a wiper for wiping the marginal portion of an upper inwardly over a sole on a last, said wiper being movable in a path inclined toward the bottom face of the last to carry the forward end of its upper-engaging portion first into engagement with the upper in a location substantially at the edge of the shoe bottom and being so mounted and controlled as to be thereafter deflected by the shoe in a path substantially parallel to said face in wiping the upper from said edge inwardly over the sole.

3. In a machine for shaping uppers over lasts, a member for laying the marginal portion of an upper inwardly over a sole on a last, said member being movable into position to act on the upper in a straight path inclined toward the bottom face of the last, and spring means controlling said member and against the resistance of which the member is arranged to be thereafter deflected by the shoe while following a path substantially parallel to the bottom face of the last in laying the upper over the sole.

4. In a machine for shaping uppers over lasts, a member for laying the marginal portion of an upper inwardly over a sole on a last, and a support for said member movable bodily in a straight path inclined toward the bottom face of the last to impart to the member its operative movement, said member being arranged to engage the upper first in a location substantially at the edge of the shoe bottom and being yieldable relatively to its support in such a direction as to be deflected by the shoe in a path substantially parallel to the bottom face of the last in laying the upper over the sole.

5. In a machine for shaping uppers over lasts, a wiper for wiping the marginal portion of an upper inwardly over a sole on a last, and a support for said wiper movable in a direction inclined toward the bottom face of the last to impart to the wiper its operative movement, said wiper being arranged to engage the upper first with the forward end of its upper-engaging portion substantially at the edge of the shoe bottom and then to be deflected by the shoe in a path substantially parallel to the bottom face of the last in wiping the upper from said edge inwardly over the sole.

6. In a machine for shaping uppers over lasts, a member for laying the marginal portion of an upper inwardly over a sole on a last, a support for said member movable in a direction inclined toward the bottom face of the last to impart to the member its operative movement, said member being arranged to engage the upper first in a location substantially at the edge of the shoe bottom and being mounted on its support for swinging movement about an axis extending lengthwise of the edge of the shoe bottom, and a spring controlling said member and against the resistance of which it is arranged to be deflected about its axis by the shoe while following a path substantially parallel to the bottom face of the last in laying the upper from the edge of the shoe bottom inwardly over the sole.

7. In a machine for shaping uppers over lasts, a member for laying the marginal portion of an upper inwardly over a sole on a last, a support for said member movable in a direction inclined toward the bottom face of the last to impart to the member its operative movement and to carry it first into engagement with the upper in a location substantially at the edge of the shoe bottom, said member being yieldable relatively to its support in response to deflecting action of the shoe thereon while following a path substantially

- parallel to the bottom face of the last in laying the upper progressively over the sole from the edge of the sole inwardly, and means for limiting the yield of said member to render it effective 5 to press the upper firmly upon the sole at the end of its operative movement.
8. In a machine for shaping uppers over lasts, a wiper for wiping the marginal portion of an upper inwardly over a sole on a last, and a support 10 for said wiper movable in a direction inclined toward the bottom face of the last to carry the forward edge of the wiper first into engagement with the shoe in a location substantially at the edge of the shoe bottom and to impart to the 15 wiper thereafter its operative movement over the shoe, said wiper being yieldable relatively to its support in such a direction as to be deflected by the shoe in a path substantially parallel to the bottom face of the last in wiping the upper over 20 the sole and having a wiping face arranged to lie substantially parallel to the bottom of the last to press the upper evenly upon the sole at the end of its operative movement.
9. In a machine for shaping uppers over lasts, 25 a member for laying the marginal portion of an upper inwardly over a sole on a last, said member being movable into position to act on the upper in a straight path inclined toward the bottom face of the last and being yieldable heightwise of the shoe in laying the upper inwardly over the sole, and means arranged to act positively on said member to increase its pressure upon the upper substantially at the end of its overlaying movement.
- 25 10. In a machine for shaping uppers over lasts, a wiper for wiping the marginal portion of an upper inwardly over a sole on a last, a support 40 for said wiper movable in a direction inclined toward the bottom face of the last to carry the forward edge of the wiper first into engagement with the shoe in a location substantially at the edge of the shoe bottom and to impart to the wiper thereafter its wiping movement over the shoe from the edge of the shoe bottom inwardly, 45 said wiper being yieldable heightwise of the shoe relatively to its support in wiping the upper inwardly.
11. In a machine for shaping uppers over lasts, 50 a wiper for wiping the marginal portion of an upper inwardly over a sole on a last, a support for said wiper movable in a straight path inclined relatively to the bottom face of the last to impart to the wiper its operative movement, said wiper being yieldable heightwise of the shoe while moving inwardly over the shoe bottom in a path substantially parallel to the bottom face of the last, and means arranged to act positively on 55 said wiper to press it firmly upon the upper substantially at the end of its wiping movement.
- 60 12. In a machine for shaping uppers over lasts, a member for laying the marginal portion of an upper inwardly over a sole on a last, a carrier for said member movable in a direction inclined 65 relatively to the bottom face of the last to impart to the member its operative movement inwardly over the shoe bottom, the member being yieldable heightwise of the shoe relatively to the carrier, and means for moving the carrier in a different direction to press said member more forcibly upon the shoe bottom substantially at the end of its 70 operative movement inwardly over the shoe bottom.
13. In a machine for shaping uppers over lasts, 75 a wiper for wiping the marginal portion of an upper inwardly over a sole on a last, a carrier for said wiper movable in a direction inclined relatively to the bottom face of the last to carry the forward edge of the wiper first into engagement with the shoe in a location substantially at the edge of the shoe bottom and to impart to the wiper thereafter its operative movement over the shoe, said wiper being yieldable heightwise of the shoe relatively to the carrier in wiping the upper inwardly, and means for imparting to the carrier movement in a different direction to press the wiper positively upon the shoe bottom substantially at the end of its wiping movement.
- 80 14. In a machine for shaping uppers over lasts, an upper-fastening device movable in a direction inclined toward the bottom face of a last into position for inserting a fastening to fasten the marginal portion of an upper to a sole on the last, and a member for laying the marginal portion of the upper inwardly over the sole, said member being movable with the upper-fastening device in the same inclined direction and arranged to be deflected by the shoe in a path substantially parallel to the bottom face of the last in laying the upper over the sole.
- 85 15. In a machine for shaping uppers over lasts, an upper-fastening device movable in a direction 100 inclined toward the bottom face of a last into position for inserting a fastening to fasten the marginal portion of an upper to a sole on the last, and a wiper for wiping the marginal portion of the upper inwardly over the sole, said 105 wiper being movable with the upper-fastening device in the same inclined direction to engage the upper first substantially at the edge of the shoe bottom and arranged to be thereafter deflected by the shoe in a path substantially parallel to the bottom face of the last in wiping the upper inwardly.
16. In a machine for shaping uppers over lasts, 110 an upper-fastening device movable in a direction inclined toward the bottom face of a last into position for inserting a fastening to fasten the marginal portion of an upper to a sole on the last, and a wiper being mounted for movement with the 115 upper-fastening device in the same inclined direction and being yieldable heightwise of the shoe 120 relatively to the upper-fastening device in response to resistance of the shoe.
17. In a machine for shaping uppers over lasts, 125 an upper-fastening device movable in a direction inclined toward the bottom face of a last into position for inserting a fastening to fasten the marginal portion of an upper to a sole on the last, and a member mounted for movement with 130 the upper-fastening device in the same inclined direction and arranged to lay the marginal portion of the upper inwardly over the sole, said member being yieldable heightwise of the shoe 135 relatively to the upper-fastening device in response to resistance of the shoe and having an upper-engaging face arranged to lie substantially parallel to the bottom face of the last to press the upper flat upon the sole at the end of the overlaying operation.
18. In a machine for shaping uppers over lasts, 140 an upper-fastening device movable inwardly over the bottom of a last into position to fasten the marginal portion of an upper to a sole on the last by a staple driven into the shoe bottom, said device comprising a staple-guiding nozzle and a deflector arranged to engage the legs of the staple prior to and during their entrance into the shoe to deflect them in curved paths such as to anchor them in the shoe, and a member movable in- 145
- 150

- wardly over the shoe bottom with said upper-fastening device between said deflector and the shoe to lay the marginal portion of the upper over the sole.
- 5 19. In a machine for shaping uppers over lasts, an upper-fastening device movable inwardly over the bottom of a last into position to fasten the marginal portion of an upper to a sole on the last by a staple driven into the shoe bottom, said device comprising a staple-guiding nozzle and a deflector arranged to engage the legs of the staple prior to and during their entrance into the shoe to deflect them in curved paths such as to anchor them in the shoe, and a member movable inwardly over the shoe bottom with said upper-fastening device between said deflector and the shoe to lay the marginal portion of the upper over the sole, said member being yieldable heightwise of the shoe relatively to the deflector. 80
- 10 20. In a machine for shaping uppers over lasts, an upper-fastening device movable in a direction inclined toward the bottom face of a last into position to fasten the marginal portion of an upper to a sole on the last by a staple driven into the shoe bottom, said device comprising a staple-guiding nozzle and a deflector arranged to engage the legs of the staple prior to and during their entrance into the shoe to deflect them in curved paths such as to anchor them in the shoe, and a member for engaging the marginal portion of the upper between said deflector and the shoe to lay the upper over the sole, said member being mounted for movement with the upper-fastening device in the same inclined direction and arranged to be deflected by the shoe in a path substantially parallel to the bottom face of the last in laying the upper over the sole. 85
- 15 21. In a machine for shaping uppers over lasts, an upper-fastening device movable in a direction inclined toward the bottom face of a last into position to fasten the marginal portion of an upper to a sole on the last by a staple driven into the shoe bottom, said device comprising a staple-guiding nozzle and a deflector arranged to engage the legs of the staple prior to and during their entrance into the shoe to deflect them in curved paths such as to anchor them in the shoe, and a member for engaging the marginal portion of the upper between said deflector and the shoe to lay the upper over the sole, said member being mounted for movement with the upper-fastening device in the same inclined direction and being yieldable heightwise of the shoe relatively to the deflector, the deflector being arranged to limit such yield of the member to increase its pressure upon the upper at the end of the overlaying operation. 90
- 20 22. In a machine for shaping uppers over lasts, an upper-fastening device movable in a direction inclined toward the bottom face of a last into position to fasten the marginal portion of an upper to a sole on the last by a staple driven into the shoe bottom, said device comprising a staple-guiding nozzle and a deflector arranged to engage the legs of the staple prior to and during their entrance into the shoe to deflect them in curved paths such as to anchor them in the shoe, and a member movable inwardly over the shoe bottom with said upper-fastening device and arranged to engage the marginal portion of the upper between the deflector and the shoe to lay the upper over the sole, said member being yieldable heightwise of the shoe relatively to the deflector and so constructed as to operate on the upper a substantial distance lengthwise of the edge of the shoe bottom at each side of the deflector. 95
- 25 23. In a machine for shaping uppers over lasts, the combination with a gripper for pulling an upper over a last successively in different locations along the edge of the shoe bottom, of a member for laying the marginal portion of the upper inwardly over a sole on the last in time relation to each upper-pulling operation, said member being movable into engagement with the shoe in a direction inclined toward the bottom face of the last and arranged to be thereafter deflected by the shoe in a path substantially parallel to said face in laying the upper over the sole. 100
- 30 24. In a machine for shaping uppers over lasts, the combination with a gripper for pulling an upper over a last successively in different locations along the edge of the shoe bottom, of a wiper for wiping the marginal portion of the upper inwardly over a sole on the last in time relation to each upper-pulling operation, and a support for said wiper movable in a direction inclined toward the bottom face of the last to carry the forward end of the upper-engaging portion of the wiper first into engagement with the shoe and to impart to the wiper its operative movement over the shoe, said wiper being yieldable heightwise of the shoe relatively to its support and arranged to be deflected by the shoe in a path substantially parallel to the bottom face of the last in wiping the upper over the sole. 105
- 35 25. In a machine for shaping uppers over lasts, the combination with a gripper for pulling an upper over a last successively in different locations along the edge of the shoe bottom, of a wiper for wiping the marginal portion of the upper inwardly over a sole on the last in time relation to each upper-pulling operation, a support for said wiper movable in a direction inclined toward the bottom face of the last to carry the forward end of the upper-engaging portion of the wiper first into engagement with the shoe and to impart to the wiper its operative movement over the shoe, the wiper being mounted on its support for swinging movement heightwise of the shoe about an axis extending lengthwise of the edge of the shoe bottom, and a spring arranged to press the wiper upon the shoe bottom and against the resistance of which it is yieldable about its axis by deflecting action of the shoe thereon to follow a path substantially parallel to the bottom face of the last in wiping the upper over the sole. 110
- 40 26. In a machine for shaping uppers over lasts, the combination with a gripper for pulling an upper over a last successively in different locations along the edge of the shoe bottom, of an upper-fastening device movable in a direction inclined toward the bottom face of the last into position for inserting a fastening to fasten the marginal portion of the upper to a sole on the last in time relation to each upper-pulling operation, and a member for laying the marginal portion of the upper inwardly over the sole, said member being mounted for movement with the upper-fastening device in the same inclined direction and arranged to engage the upper first substantially at the edge of the shoe bottom and then to be deflected by the shoe in a path substantially parallel to the bottom face of the last in laying the upper over the sole. 115
- 45 27. In a machine for shaping uppers over lasts, the combination with a gripper for pulling an upper over a last successively in different locations along the edge of the shoe bottom, of an upper-fastening device movable in a direction inclined toward the bottom face of the last into position 120
- 50
- 55
- 60
- 65
- 70
- 75

for inserting a fastening to fasten the marginal portion of the upper to a sole on the last in time relation to each upper-pulling operation, said device comprising a staple-guiding nozzle and a deflector arranged to engage the legs of the staple prior to and during their entrance into the shoe to deflect them in curved paths such as to anchor them in the shoe, and a member for laying the marginal portion of the upper over the sole adjacent to said deflector, said member being mounted for movement with the upper-fastening device in the same inclined direction and being yieldable in response to deflecting action of the shoe thereon to follow a path substantially parallel to the bottom face of the last in laying the upper over the sole.

28. In a machine for shaping uppers over lasts, the combination with a gripper for pulling an upper over a last successively in different locations along the edge of the shoe bottom, of an upper-fastening device movable in a direction inclined toward the bottom face of the last into position for inserting a fastening to fasten the marginal portion of the upper to a sole on the last in time relation to each upper-pulling operation, said device comprising a staple-guiding nozzle and a deflector arranged to engage the legs of the staple prior to and during their entrance into the shoe to deflect them in curved paths such as to anchor them in the shoe, and a wiper for wiping the marginal portion of the upper inwardly over the sole between said deflector and the shoe, said wiper being mounted for movement inwardly over the shoe bottom with the upper-fastening device and being yieldable heightwise of the shoe in response to deflecting action of the shoe thereon.

29. In a machine for shaping uppers over lasts, the combination with a gripper for pulling an upper over a last successively in different locations along the edge of the shoe bottom as the shoe is presented successively by the operator in different positions bottom upward, of a member for laying the marginal portion of the upper inwardly over a sole on the last in time relation to each upper-pulling operation, said member being movable in a forwardly and downwardly inclined direction toward the bottom of the shoe and arranged to be deflected by the shoe in a path more nearly horizontal and substantially parallel to the shoe bottom in laying the upper over the sole.

30. In a machine for shaping uppers over lasts, the combination with a gripper for pulling an

upper over a last successively in different locations along the edge of the shoe bottom as the shoe is presented successively by the operator in different positions bottom upward, of a member for laying the marginal portion of the upper inwardly over a sole on the last in time relation to each upper-pulling operation, and a support for said member movable in a forwardly and downwardly inclined direction to impart to the member its operative movement, said member being so mounted on its support as to permit it to yield in an upward direction upon engagement with the shoe while following a path more nearly horizontal and substantially parallel to the shoe bottom in laying the upper over the sole.

31. In a machine for shaping uppers over lasts, the combination with a gripper for pulling an upper over a last successively in different locations along the edge of the shoe bottom as the shoe is presented successively by the operator in different positions bottom upward, of a member for laying the marginal portion of the upper inwardly over a sole on the last in time relation to each upper-pulling operation, a support for said member movable in a forwardly and downwardly inclined direction to carry the forward end of the member first into engagement with the shoe and to impart to the member its operative movement over the shoe, said member being mounted on its support for swinging movement heightwise of the shoe, and a spring tending to swing the member downwardly while permitting it to yield in an upward direction in response to the action of the shoe thereon while following a path substantially parallel to the shoe bottom in laying the upper over the sole.

32. In a machine for shaping uppers over lasts, the combination with a gripper for pulling an upper over a last successively in different locations along the edge of the shoe bottom as the shoe is presented successively by the operator in different positions bottom upward, of a wiper for wiping the marginal portion of the upper inwardly over a sole on the last in time relation to each upper-pulling operation, a support for said wiper movable in a forwardly and downwardly inclined direction to impart to the wiper its operative movement, the wiper being yieldable heightwise of the shoe while moving inwardly over the sole in a path substantially parallel to the bottom face of the last, and means for pressing said wiper positively downward upon the shoe bottom substantially at the end of its wiping movement.

CERTIFICATE OF CORRECTION.

Patent No. 1,927,941.

September 26, 1933.

AXEL E. LINDBLAD.

It is hereby certified that error appears in the printed specification of the above numbered patent requiring correction as follows: Page 4, lines 118 and 119, claim 16, strike out the words "tion of the upper inwardly over the sole, said marginal portion of an upper to a sole on the" and insert instead last, and a wiper for wiping the marginal portion of the upper inwardly over the sole, said; and that the said Letters Patent should be read with this correction therein that the same may conform to the record of the case in the Patent Office.

Signed and sealed this 28th day of November, A. D. 1933.

(Seal)

F. M. Hopkins
Acting Commissioner of Patents.
